Primary Examiner — Susan Bennett Hattan*Assistant Examiner* — Janice Hallmark(74) *Attorney, Agent, or Firm* — Goldstein Law Offices, P.C.(57) **CLAIM**

The ornamental design for a magnetic tobacco article retainer, as shown and described.

DESCRIPTION

FIG. 1 is a perspective view of the magnetic tobacco article retainer.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof.

FIG. 8 is a second alternate perspective view thereof shown with environment; and,

FIG. 9 is a third alternate perspective view thereof.

The broken lines in the drawings depict environmental subject matter only that forms no part of the claimed design.
